UNITED STATES PATENT OFFICE.

MARTIN HOLLAND, OF LAURENS, IOWA.

WEED-DESTROYING ATTACHMENT FOR RAILWAY CARS.

Application filed November 9, 1926. Serial No. 147,258

This invention relates to improvements in weed destroying attachment for railway cars, and particularly designed to be attached to the small motor cars used by section hands, and when attached is adapted to destroy weeds along the grade adjacent to the ends of the ties.

The object of my invention is to provide a weed destroying attachment of simple, durable and inexpensive construction which may be easily and quickly attached to the ordinary motor car used by section hands, and when attached is adapted to cultivate and stir the soil or the ballast of the road bed adjacent to the ends of the ties in such a manner as to destroy the weeds growing in the space covered by the cultivating attachment, and at the same time provide means whereby the crown of the grade slope may be maintained at a minimum cost.

More specifically it is the object of my invention to provide a pair of detachable frame members, one for each side of the motor car, each of the frame members being provided with a beam which may be adjusted at various angles relative to the motor car, and at various elevations, and at various distances toward and from the car, said beam being provided with a series of cultivating disks for stirring the ground surface, and each of said disks being independently supported so that its angle relative to the beam may be adjusted to meet various working conditions.

A further object is to provide a weeding or cultivating attachment for motor cars so constructed and arranged that a maximum amount of work may be performed with a minimum amount of power, and at the same time permitting the weeds and trash to pass through and between the cultivating members without tangling.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is an end elevation of a motor car showing the manner in which my improved device is attached thereto, one of the weeding members being removed.

Figure 2 is a plan view of one of the weeding members and its supporting frame, together with a portion of the motor car frame.

Figure 3 is a detail, side elevation of the

windlass for elevating and lowering the weeding element and its support.

The numeral 10 indicates generally the motor car having a frame member comprising a pair of spaced side members 11 at each side of the car, and end members 12. The end members are bolted between the side members. The lower ones of the side members 11 are supported on axles 13 having wheels 14. Adjacent to the inner face of each of the end members 12 I have provided a pipe 15 having its ends projecting through the space between the members 11 and each end being screw threaded. Each end of the pipe 15 is provided with a plate 16 designed to rest against the outer surface of the members 11 and locked in position by means of nuts 17. This provides means for anchoring the pipe 15 in position, said pipe being permitted to remain permanently after once installed.

Each end of the said pipe 15 is designed to receive an eye bolt 18. That portion of the eye bolt extending within the pipe is provided with a series of openings which register with openings 19 in the pipe 15. Said openings are designed to receive a pin 20 which provides means whereby the eye bolt may be adjusted inwardly or outwardly. The corresponding I-bars of each side of said car are designed to receive a pipe or frame member 21 rotatively mounted therein.

Said frame member 21 is held against longitudinal movement by means of suitable pins 22. Pivotally mounted on each of the frame members 21, near each end, are laterally extending frame members 23, the outer end of each member 23 being provided with a series of openings 24. Said outer ends are designed to receive a beam 25, each end of said beam being adjustably mounted thereon by means of a pin 26 extending through the openings 24. The beam 25 is provided with a series of downwardly extending shanks 27. The upper ends of said shanks are screw threaded and extend through the beam. Each of the shanks is slidably and rotatively mounted in said beam and set to any desired position of movement by means of nuts 28. The lower end of each of the shanks is provided with a cultivator disk 29. The disks may be adjusted at various angles relative to each other or to a longitudinal line of movement of the car, and the depth of the disks may be also adjusted by moving the shanks longitudinally through the supporting beam.

Figure 3 is a detail, side elevation of the

The central portion of the frame member 21 is provided with a pair of upwardly extending supports 30, the upper ends of which are designed to rotatively support a crank 5 shaft 31 provided with a cable drum 32 and also a ratchet wheel 33. Said ratchet wheel is engaged by the pawl 34 which prevents rotation of the drum 32 in one direction. One end of the cable 35 is secured to the drum 32, 10 while the other end is secured to the central portion of the beam 25.

The upper ends of the supports 30 are held against movement by means of a tie bar 36, while the lower ends of said supports are 15 held against inward movement by means of a strap 37 which extends inwardly from the lower ends 30 and engages the outer surface of the upper ones of the side members 11.

The front disk of each set of disks 29 is 20 preferably set in a plane substantially at right angles to the plane of the adjacent disk, in such a manner that the soil adjacent to the ends of the ties will be moved outwardly and any weeds cut loose. The adjacent disk will 25 again move the soil inwardly as the motor car is advanced over the track, thereby providing means whereby the soil adjacent to the ends of the ties may be freed from weeds. In practical operation the disks 29 are 30 permitted to engage the surface of the slope portion of the grade and the cables 35 loosened to permit the said disks to follow the contour of the surface. The soil will then be cultivated and stirred in such a manner that 35 all weeds will be cut loose or covered. The disks are mounted independently so that weeds and trash will pass between them without tangling. The disks may be set at any desired angle so the slope of the grade may 40 be properly maintained.

The beam 25 may also be moved toward or from the frame member 21, as well as the angle of said beam being adjustable relative to the line of movement of the car, thereby 45 providing means whereby said device is very flexible as to adjustment, so it may be made to accomplish the desired result.

The disks may be easily and quickly elevated to position adjacent to the sides of the 50 uprights 30 when moving from one place of work to another, or when it is desired to move the car from the track to accommodate passing trains. In this connection it should be noted that the frame work, being made of 55 tubular construction, is very light, and at the same time sufficiently strong to support the weeding elements. This is very essential on account of the car having to be lifted from the track to accommodate passing trains.

60 Another important feature of my invention lies in the fact that the weeder attachment may be quickly removed when so desired by simply removing the pins 22 and the bolts from the brace 36, after which the 65 bars 18 may be slid from the ends of the

pipes 15, permitting the entire weeder attachment to be quickly removed. The motor car may then be used for any other desired purpose. It should be borne in mind that the weeder attachment will only be used about 70 three months out of the year, and the weeder attachment may be stored away in a very compact form when not in use.

Thus it will be seen that I have provided a 75 weeder attachment for small motor cars for railways of simple, durable and inexpensive construction, which may be easily and quickly attached or removed, and in which a very 80 small initial cost is necessary to convert any ordinary motor car into a weeder mechanism 85 which is capable of maintaining a large amount of road grade at a very small cost.

I claim as my invention:

1. In a railway weed destroyer, the combination with a railway car, of an auxiliary frame having a pair of laterally extending pivoted arms, a beam adjustably secured to the free ends of said arms to move toward and from said car and capable of having its angularity adjusted relative to the line of 90 advance of said car, means for elevating and lowering said beam, and a series of disks carried by said beam, and means for adjusting the angle of each of said disks relative to said beam and to the line of advance of said 95 car.

2. In a railway weed destroyer, the combination with a railway car, of an auxiliary frame having laterally extending pivoted arms, a beam adjustably secured to the free 100 ends of said arms to move toward and from said car and capable of having its angularity adjusted relative to the line of advance of said car, means for elevating and lowering said beam, a series of disks carried by said 105 beam, means for adjusting the angle of each of said disks relative to said beam and to the line of advance of said car, and means for adjusting the depth of said disks relative to each other.

3. In a railway weed destroyer, the combination with a railway car, of a pair of parallel and spaced pipes, means for securing said pipes transversely to the frame of said car, an eye bolt slidably mounted in each end of 115 said pipes, means for locking said eye bolts in position, a frame member mounted in each corresponding set of eye bolts, a laterally extending frame member pivotally mounted to each end of the first said frame member, 120 a beam adjustably mounted on the outer ends of said corresponding laterally extending frame members, said beam being provided with a series of vertically arranged shanks 125 rotatively and slidably mounted therein, means for adjusting said shanks at various positions of their movement, a disk for each of said beams, and means for elevating and lowering said beams.

4. In combination with a railway car, of a 130

pair of pipes, means for securing one of said pipes to each end of said car, an eye bolt slidably mounted in each end of each of said pipes, means for adjustably locking said bolts in position, a frame member mounted in each corresponding set of eye bolts, a laterally extending frame member pivotally mounted to each end of the first said frame member, a beam adjustably mounted on the outer ends of said corresponding laterally extending frame members, said beams being provided with a series of vertically arranged

shanks rotatively and slidably mounted therein, means for adjusting said shanks at various positions of their movement, a disk 15 for each of said shanks, means for elevating and lowering said beams, said means comprising a windlass support, a windlass for said support, and a cable having one end connected to said windlass and its opposite end 20 to said beam.

Des Moines, Iowa, October 28, 1926.

MARTIN HOLLAND.
